SERVICE STATION CANOPY

Robert J. Harper, Scarsdale, N.Y., assignor to North-
western Refining Co., St. Paul Park, Minn., a corpora-
tion of Minnesota

Filed July 30, 1963, Ser. No. 76,032

Term of patent 14 years

(Cl. D13—1)

FIG. 1

FIG. 2

FIG. 3

FIG. 4

FIGURE 1 is a perspective view of a service station canopy, showing my new design.

FIGURE 2 is a front elevation of the design shown in FIGURE 1.

FIGURE 3 is a perspective view of the roof of said service station canopy, as seen from the underside thereof, the supporting standards being broken away.

FIGURE 4 is an end elevation.

The gasoline pumps and stand shown in broken lines in FIGURES 2 and 4 are disclosed for illustrative purposes only.

I claim:

The ornamental design for a service station canopy, as shown and described.
